UNITED STATES PATENT OFFICE.

FRANK L. UNDERWOOD, OF VERMONT, ILLINOIS.

DESIGN FOR A FOOTSTOOL.

SPECIFICATION forming part of Design No. 31,653, dated October 10, 1899.

Application filed September 13, 1899. Serial No. 730,387. Term of patent 7 years.

To all whom it may concern:

Be it known that I, FRANK L. UNDERWOOD, of Vermont, in the county of Fulton and State of Illinois, have invented and produced a new and original Design for a Footstool, of which the following is a full, clear, and exact description.

Reference is to be had to the accompanying drawing, forming a part of this specification, in which the figure represents a perspective view of a footstool, showing my design.

The design in its entirety consists of an ornamental base A, appearing at the corners with legs B, and from the base rises the stool-top, having a transversely-extending raised semicircular ridge C, flanked at its sides by the horizontal portions D D', rounded off at

the junction of the ends of the base A, the junctions between the horizontal portions and the ridge C being formed by rounded-off corners E.

The leading feature of the design consists of the top with the ridge flanked by the horizontal portions.

Having thus described my invention, I claim as new and desire to secure by Letters Patent—

The design for a footstool herein shown and described.

FRANK L. UNDERWOOD.
